UNITED STATES PATENT OFFICE.

JOSEPH LUPO, JR., OF NEW YORK, N. Y.

NAIL BUFFER.

Application filed October 30, 1922. Serial No. 597,875.

To all whom it may concern:

Be it known that I, JOSEPH LUPO, Jr., a citizen of the United States, and a resident of the city of New York, borough of the Bronx, in the county of Bronx and State of New York, have invented a new and Improved Nail Buffer, of which the following is a full, clear, and exact description.

This invention has relation to manicuring articles and has particular reference to an improvement in nail buffers of the type which are provided with means for removably associating the chamois or other polishing cloth with the buffer proper.

One of the principal objects of the present invention is to provide a nail buffer of the character set forth in which means is afforded for facilitating the application and removal of the chamois or other polishing cloth from the buffer.

As a further object the invention resides in the provision of a nail buffer in which the body or holder and the back are constructed from an integral piece of material which is padded and encased in a permanent covering over which the removable chamois or polishing cloth is stretched and retained against displacement.

As a further object the invention contemplates a handle construction for the buffer which greatly adds to the comfort of the manipulator of the buffer during its use.

A still further object of the invention resides in the provision of a buffer of the character described which is extremely simple in its construction, inexpensive to manufacture and which is highly efficient in its purpose.

With the above recited and other objects in view, the invention resides in the novel construction set forth in the following specification, particularly pointed out in the appended claims and illustrated in the accompanying drawing, it being understood that the right is reserved to embodiments other than those actually illustrated herein to the full extent indicated by the general meaning of the terms in which the claims are expressed.

In the drawing—

Figure 1 is a side view of a nail buffer constructed in accordance with the invention, parts being broken away and shown in section to disclose the underlying structure.

Fig. 2 is a cross sectional view taken approximately on the line 2—2 of Fig. 1.

Fig. 3 is a perspective view of the removable chamois or polishing cloth retaining means disassociated from the buffer.

Fig. 4 is a sectional view taken approximately on the line 4—4 of Fig. 1 and illustrating the construction of the handle.

Referring to the drawings by characters of reference, 10 designates the body of the buffer which is of rectangular configuration and is formed with an enlarged integral back 11, said elements being preferably constructed of wood or any other suitable material. The body 10 is covered at its sides with a padding consisting of a felt strip 12 completely encasing the sides and ends of the body. A plurality of felt strips 13 are attached to the lower face of the body and a permanent covering 14 which is preferably of chamois encases the padding strips 12 and 13. The removable chamois or other polishing material 15 is designed to be stretched over the permanent cover 14 with the free edges 16 of said polishing material turned outwardly under the shoulders 17 formed by the edges of the back which protrude beyond the sides and ends of the body 10. A retaining element 18 which is of similar configuration to the body 10 is forced over the polishing material after the same has been stretched in place, said retaining element serving the purpose of operatively associating the removable polishing material with the buffer proper.

The internal configuration of the retaining element 18 is of smaller dimension than the external configuration of the body, backing and permanent covering 14 whereby when the retaining element is forced into place the padding will be compressed to such an extent as to prevent casual displacement of the retaining element and removable polishing material. The retaining element is further provided with a marginal flange 19 at its upper edge which underlies the shoulder 17 and grips the outturned edges of the removable polishing material against the under side of said shoulder. This flange also constitutes a means for facilitating the removal and application of the retaining element and the removable polishing material from the buffer proper.

A handle 20 is connected to the back 11 by a pair of spaced arms 21 and a yieldable band 22 preferably of rubber or other elastic ma-

terial embraces the arms 21 to render the manipulation of the buffer more comfortable to the user.

I claim:

5. 1. A nail buffer comprising a buffer body, having yieldable bottom and side faces adapted to receive thereover a removable polishing material, and means consisting of a substantially annular band of lesser internal diameter than the external diameter 10 of the body with the removable polishing material applied, for embracing and retaining the polishing material in covering relation on the body by inward pressure of the 15 band into the sides of the yieldable body.
2. A nail buffer, a buffer body having padded side and bottom walls over which a removable polishing material is arranged in covering relation, and an endless band 20 of lesser internal diameter than the external diameter of the buffer body adapted to be forced thereover for producing by compression a marginal groove in the side walls into which the removable polishing material is forced for effecting its retention 25 on the buffer body.
3. A nail buffer comprising an integral body and backing, said backing being of a larger size than the body to provide a 30 marginal shoulder at the upper end of the

body, yieldable padding completely encasing said body, a permanent covering for said padding, a removable polishing material stretched over the permanent covering, and means for embracing and retaining the polishing material in covering relation over the permanent covering and padded body, said means comprising a substantially annular member having a flange at its upper end which bears against the 35 marginal shoulder of the buffer.

4. A nail buffer comprising an integral body and backing, said backing being of a larger size than the body to provide a marginal shoulder at the upper end of the body, 45 yieldable padding completely encasing said body, a permanent covering for said padding, a removable polishing material stretched over the permanent covering, means for embracing and retaining the polishing material in covering relation over the permanent covering and padded body, said means comprising a substantially annular member having a flange at its upper 50 end which bears against the marginal shoulder of the buffer, a handle carried by the backing, and a casing of yieldable material embracing said handle.

JOSEPH LUPO, Jr.
